UNITED STATES PATENT OFFICE.

THOMAS C. THOMAS, OF PEORIA, ILLINOIS, ASSIGNOR OF ONE-HALF
TO DANIAL R. SHEEN, OF PEORIA, ILLINOIS.

GRAIN-DOOR.

No. 806,209.

Specification of Letters Patent.

Patented Dec. 5, 1905.

Application filed August 27, 1904. Serial No. 222,524.

To all whom it may concern:

Be it known that I, THOMAS C. THOMAS, a citizen of the United States, residing at Peoria, in the county of Peoria and State of Illinois, have invented certain new and useful Improvements in Grain-Doors; and I do hereby declare that the following is a full, clear, and exact description of the invention, which will enable others skilled in the art to 10 which it appertains to make and use the same.

This invention pertains to improvements in doors for railway-cars.

The primary object of this invention is to 15 provide a door for railway-cars that will close into the doorway from without and that will open outwardly from the wall of the car, so that the lading when resting or bearing against said door will not prevent it being easily 20 opened.

Another object of this invention is to provide a door that will serve a double purpose—namely, that will serve as a grain-door and at the same time serve as an outer door to 25 protect the contents of the car from the weather and marauders.

Another object of the invention is to provide a door that may be carried on the wall of the car within the doorway when closed 30 and moved along the wall away from the doorway when not in use.

Another object of the invention is to provide a door that is attached to the car and not in danger of being lost or carried away.

Another object of the invention is to provide a door so arranged that the act of opening the door also places it out of the way and where it will safely ride at the side of the car until its use is again demanded.

In addition to the above there are various other points of advantage gained by this invention, one of which is the addition it affords to the permanent equipment of railway-cars and the advancement it contributes to the 45 art of building and equipping cars for their greatest efficiency.

Long experience demonstrates that any kind of door placed inside of the car to close or partially close the doorway is impractical, such doors having been applied in various forms; but almost complete failure has resulted from their use. Such doors have so many disadvantages that they of necessity have been abandoned. The last resort in 55 the use of what has been called a "grain-

door" provides that cheap doors shall be constructed and shipped to all points where grain in the bulk is loaded into cars, and each time a car is to be laden its doorways are closed with these cheap doors. When the 60 car is to be unloaded, the door is broken down, removed, and taken away for kindling-wood, and thus the cars go their way hither and thither unequipped with doors, although the cost of a door is expended every time a 65 car is loaded. It will be seen that this invention in closing the door preparatory to loading the car seats the door snugly, firmly, and securely in the doorway, and it is retained there, leaving the upper portion of the doorway open to receive the load, whether it be grain in the bulk, vegetables, brick, coal, or ear-corn, and when loaded the upper part of the doorway is closed and the whole locked and sealed. It will furthermore be seen that 75 when it is desirable to unload the car after the seal is broken and the door unlocked said door can be moved upon its bearings outwardly, no matter how heavily the lading may press against it, although it may be sustaining coal or brick within the car.

As the door is withdrawn from the doorway it is transferred to the frame that carries it with but very little effort, and hanging within the frame, either flush with it or 85 even outside of it, will ride smoothly along the track without touching the side of the car.

It will be seen that when the frame with its door has been pushed up in front of the 90 doorway means is provided for securing the foot of the door firmly to the car. Also when the door has been transferred from the frame to the doorway and its upper portion closed means are employed to hold the latter 95 securely in its place.

The lower portion of the door is adapted to the doorway and may be transferred with ease from said doorway to its frame, and vice versa, with perfect ease and precision.

Having pointed out the object of the invention and some of the advantages therein and the gain to be derived from it, I shall proceed to the specification, aided by the accompanying drawings, in which—

Figure 1 is a perspective view of a portion of the side of a car, showing my improved door placed thereon. Fig. 2 is a vertical end section of the car, showing the door in cross-section mounted on the frame, which is sup-

100

105

110

ported from the track above the door-opening. Fig. 3 is a horizontal section of part of the door and the frame that supports it. Fig. 4 is an edge view of the same. Fig 5 is 5 an enlarged view of a slotted hinge for the door. Fig. 6 is a partial section of the door and door-jamb, showing a latch for keeping the door closed.

A indicates the side of the car, showing the 10 door-opening, above which is a track B, secured in place in any good manner and extending considerably to one side of the said opening, as shown. The door-opening is of two dimensions, the larger of the two designed 15 to receive the door and the other being the jamb against which the door rests when in its closed position, the said jamb being represented by C. Hung from the track B by means of the ordinary hangers D and 20 rollers E is an open frame F, preferably of metal, although wood can be made to answer, if desired. Said frame is designed to run along the track and cover the opening of the doorway, as will be presently understood.

25 At G in four places is secured a boxing carrying a crank-arm H, (shown in Fig. 3,) and inside the frame is located the door which serves to close the door-opening, as shown in Fig. 2. This door is composed of two sections I and J, hinged together at K. The section I carries at four places a boxing L, similar to G just described, said boxing being in the vicinity of G, as shown, and receiving the ends of the crank-arms described. 30 By this means it will be seen that the said door I J is carried pivotally on the frame F by means of the cranks, the latter being so placed that the door is permitted to swing toward and away from the car, but in a vertical plane at all times.

It is well known to grain men and those 45 about railway-cars and elevators that doors for closing cars must be quite simple and light and easily locked and unlocked, since a man handling cars and grain will take no time or patience to properly open one. If the door cannot be easily manipulated, he will use a crowbar or other implement and pry it open and end in breaking it to pieces 50 and rendering it unfit for further use. Having this in mind, I have devised the door herein described, and the particular purpose thereof is to operate it by pushing it toward the car or drawing it away therefrom. In 55 this way it can be readily set in place or withdrawn with the least effort. For this purpose the door is mounted by means of the said cranks H, which permit it to operate as described. The bottom edge of the door is 60 beveled, as shown in Fig. 2, and a socket of the same form is created by cutting away the floor of the car, as at M, so that the door will sit therein and make a tight joint, an opening N being left the full width of the door to 65 permit dirt and obstacles of one kind or an-

other filling in beneath the door and preventing it closing. I provide at O a pair of handles by which the door may be readily taken hold of.

In Fig. 1 the door is shown open and 70 pushed along the track. If it is desired to close said door, the frame F is pushed along the track until it meets the stops P, secured in the side of the car. This brings the door just opposite the door-opening, and by grasping 75 the handles O the door is now pushed toward the opening, swinging meanwhile upon the cranks and dropped in place in the said socket at M. This action places the door in a position to rest of its own weight in the 80 closed position and perfectly vertical by reason of the cranks.

The upper portion J of the door is designed to rise and fall relatively to the portion I, and this is permitted by the hinges K referred to, 85 which are constructed as shown in Fig. 5, the upper portion being slotted at K' in order to move up and down on the pivot-pin K² of said hinge. When raised, as shown in Figs. 1 and 5, the upper door portion J can be readily 90 opened outward, as shown in Fig. 1 referred to; but when placed in a vertical position, as shown in Fig. 5, and dropped to the position shown in broken lines the slotted hinge-section forms a lock with the lower 95 portion I and prevents the door being opened. At the top of the said door-section J is a spring-latch Q, operated by a cord or wire R from the ground. This latch is adapted to engage a socket at S in the doorway, acting 100 as a keeper for said latch when the door portion J is closed. In order to form a strong lock, I provide at T a bar hinged to the section J above the line of its hinges, while at U U are two staples, one of which is secured 105 in the upper section and the other in the lower one. A slot V in two places in the said bar T receives the staples when the door is closed, and pins may be passed through the staples to lock the bar in a rigid position, 110 thus preventing the door being opened when said pins are locked with the usual seal. In lieu of this a padlock could be placed in each staple.

To open the door, the latch Q is drawn 115 down by means of the wire R, the section J raised to liberate the hinges, and then by grasping the handles O the section I is raised out of its socket, raised on its cranks, and drawn forward and permitted to rest on a stop V, secured to the frame F, as shown in Figs. 1 and 2. The upper section is allowed to hang down over the lower one, so that it is entirely out of the way of the car. In fact, there is nothing extends beyond the plane of 120 the frame F at the back, so that said frame can be readily slid along its track without hindrance. As constructed in the drawings, the upper section J is given sufficient play at 125 the top within the opening to allow it to be 130

raised after pulling down the latch Q, so that the said section can free its hinges for the purposes described.

Handles may be placed upon the upper door-section, if desired, and other changes within the scope of the invention may be made. For instance, the equivalents of the cranks H may be used, and more or less of them may be employed than shown. Likewise some other form of locking arrangement for the upper section may be used, as I do not wish to confine myself to any particular means in that direction; but my aim and desire is to provide a door that can be operated substantially in the manner described—that is to say, one that can be readily moved away from the doorway entirely out of the way or when opposite said doorway can be easily dropped into it by the crank-motion described and shown.

I desire to state that it is not absolutely necessary that the door I J should move in a vertical plane; but it must come to a vertical position when seating in the doorway. It will be seen that the door is firmly locked in place by means of the bevel at M at the floor of the car and by means of the latch Q, aided by the bar T, at the hinge-line. The lower half of the door, however, will when placed in the doorway serve to lock itself by resting in the socket M, being held thereby from outward movement due from pressure of freight within the car. When thus positioned, the cranks H then prevent the frame from swinging outward. The door can in this way be used for freighting where but one-half of the door is necessary, thus giving added advantages.

I claim—

1. In a grain-door the combination of a frame larger than the doorway of the car, a track secured at the side of the car above the doorway, the said frame slidably hung therefrom, a lower door-section on the frame, a series of cranked members each having a horizontal bearing at one end on the said door-section, the opposite extremities of the cranks also having a horizontal bearing on the suspended frame for carrying the door through said frame in the manner described, the bottom edge of the section being beveled as shown, there being a socket in the car-floor for receiving the said door, the latter seating and closing by its own weight after being carried through the frame, an upper door-section, hinges for connecting said upper and lower section, one of the portions of each hinge being slotted to permit movement of the upper section on the lower in a vertical direction at the time and for the purposes described, and means for locking both sections together and preventing movement of the door from the doorway while thus locked.

2. In a grain-door, a track above the door-

way, an open frame hung therefrom and slideable thereupon for the purposes set forth, a lower section, cranked members horizontally journaled on the door-section and on the frame for carrying said section when swung inward through the frame to its limit of movement to rest in the doorway, there being a socket in the floor for receiving the section, a stop on the outside of the frame for receiving the lower edge of the section when swung outward, an upper section hinged to the lower and adapted to have vertical movement therein as set forth, and locking means between the two sections for locking them together in one plane within the doorway as set forth.

3. In a grain-door, a track above the doorway, a frame suspended therefrom and slideable thereon, a lower half-door section, horizontal cranked members for permitting the said sections to swing in a vertical arc through the frame, an upper half-door section hinged to the lower one and adapted to hang therefrom, said lower section adapted to seat in the doorway, there being a socket for receiving it, the socket and the cranked members locking the section in place as described.

4. In a grain-door, a track above the doorway of the car, a frame hung therefrom and slideable thereon, a lower door-section, cranks for supporting the door-section on said frame and for carrying the said sections in a vertical arc, when moved through the frame, there being a socket in the floor of the car at the doorway, the lower edge of the section resting in said socket when closed and forming thereby a lock as described the cranks also holding the frame from movement for the purposes set forth.

5. In a grain-door, a track above the doorway of the car, a frame suspended therefrom and adapted to travel along the same, a lower door-section, crank members having horizontal bearings on the door-section and the frame as set forth for permitting movement of the section in the manner described, an upper door-section, slotted hinges connecting the two sections, said hinges permitting the upper section to hang down against the lower one, and also permitting separation of the sections when lying in one plane for the purposes set forth, means for locking the sections together at the juncture of the two after the lower section has been placed within the doorway there being a socket in the floor of the car for receiving the said lower section.

In testimony whereof I affix my signature in presence of two witnesses.

THOMAS C. THOMAS.
